UNITED STATES PATENT OFFICE.

ARTHUR S. GILMAN, OF CLEVELAND HEIGHTS, OHIO, AND JOHN E. DOODY, OF TORONTO, ONTARIO, CANADA; SAID DOODY ASSIGNOR TO SAID GILMAN.

CARBON-SHEET HOLDER.

Application filed December 19, 1923. Serial No. 681,634.

To all whom it may concern:

Be it known that we, ARTHUR S. GILMAN, a citizen of the United States, resident of the city of Cleveland Heights, county of Cuyahoga, and State of Ohio, and JOHN E. DOODY, a citizen of the Dominion of Canada, city of Toronto, county of York, Province of Ontario, and Dominion of Canada, have invented new and useful Improvements in Carbon-Sheet Holders, of which the following is a specification, the principle of the invention being herein explained and the best mode in which we have contemplated applying that principle, so as to distinguish it from other inventions.

Our invention relates to holders for carbon-sheets used in connection with duplicating type-writing machines, and which carbon-sheets are ordinarily known in the art as "floating carbons."

Heretofore it has been customary in this class of devices, to provide transverse holding means or bars to which the ends of the carbon-sheets were directly attached as shown, for example in the Smith Patent No. 1,177,546, this structure being now generally employed in connection with the Underwood duplicating type-writing machine.

These heretofore used constructions furthermore have been such that a considerable part of the end portions of the carbons which are attached could not be used for duplicating purposes and hence was wasted. Furthermore, and especially in the Underwood machine, the bars are stepped from each other longitudinally, that is, in the direction of feed of the carbon-sheets. This necessitated trimming off the front ends of these carbon-sheets to make them register, which entailed a further waste of the material of such sheets.

In addition, the attachment of the carbon-sheets directly to the holding bars, on account of the greater flexibility and thin character of the carbon-sheets, made it necessary to use considerable care in such attachment in order to bring the lateral edges of the carbon-sheets in lines exactly parallel with the direction of feed thereof, in order that they might pass properly between the platen and pressure rolls.

The object of our invention is to provide means whereby such above-mentioned waste is eliminated, the carbon-sheets may be easily attached and removed from the hold-

ing bars, and whereby they may be easily placed in said position in which their edges are exactly parallel with the line of feed.

To this end, our invention comprises a member to which the end of the carbon-sheet may be readily and accurately attached and which may be readily and accurately attached to the holding bars, thereby providing an element intermediate to the end of the carbon-sheet and the holder which is designed to actuate it.

The said invention consists of means hereinafter fully described and particularly set forth in the claims.

The annexed drawings and the following 70 description set forth in detail certain means embodying our invention, the disclosed means, however, constituting but one of the various mechanical forms in which the principle of the invention may be employed. 75

Figure 1 represents a plan of that part of an Underwood duplicating type-writing machine including the carbon-sheet operating mechanism.

Fig. 2 represents a longitudinal section 80 taken upon the plane indicated by line II-II, Fig. 1.

Fig. 3 represents a detailed longitudinal section taken upon the plane indicated by line III-III, Fig. 1. 85

Fig. 4 represents a plan of one of the intermediate members forming part of my invention.

Figs. 5 and 6 represent respectively a plan and side elevation of one of the clips used 90 in connection with the securing of the carbon-sheets to the intermediate members.

The illustrated embodiment of our invention includes a flat element 1, preferably made of thin, but comparatively stiff, paper. 95 By comparatively stiff we mean stiff as compared with the ordinary sheet of carbon-paper.

This element is formed with a transverse body-member 2, a central longitudinal extension 3 projecting from the body member centrally thereof, and two flaps 4-4 which are hinged (preferably by being integrally united) to the transverse edges 5-5 of the body member 2 which are adjacent to the 105 edges 3, all as shown in Fig. 4. The other edge portion 6 of the body member is preferably reinforced with the light cloth material 7 which provides a reinforcement for such edge portion. 110

These flaps 4—4 are adapted to be folded down against the adjacent portion of the body member 2.

Each sheet of carbon paper is secured to 5 one such element 1, such attachment being effected by slipping the one edge portion of such carbon-sheet beneath the flaps 4—4 until they contact the inner extremity of the 10 angles formed by the flaps with the body portion 2 of the element 1, the lines of the apices of these solid angles being in alinement with each other and at right angles with the axis of the element, as shown in Fig. 4. This brings the longitudinal edges 15 of the carbon-sheet parallel with the axis of the element 1, and said sheet is secured in such position by slipping two clips 8, over the flaps, one over each of the latter as shown in Fig. 4. These clips may be made 20 of any suitable form, as will be readily understood. The clips bear down upon the flaps and press same against the intermediate carbon-sheet so as to secure the latter between the flaps and the body member 2.

25 The free end of the extension 3 is then secured centrally to one of the transverse carbon-sheet holding bars 9 of the carbon-sheet holding and operating mechanism by securing same between said bar and the 30 hinged clamping member 10 of such bar. The free transverse edge 11 of this extension is formed accurately at right angles to the axis of the element 1 so that this free edge may, when the extension is so secured, be 35 caused to assume a position exactly parallel with the direction of feed of the carbon-sheet. The stiffness of this element will lend itself to this accuracy of adjustment.

These holding bars are, in the type of machine to which this invention is shown to be applied, stepped from each other in the direction of carbon-feed as is well known to those skilled in the art.

To compensate for this stepped arrangement, we provide elements 1 having different lengths of extensions 3, as is shown in dotted lines in Fig. 4, the difference in these lengths corresponding to the longitudinal difference in the position of the axes of the 45 holding bars 9. Elements 1 are selected for attachment to the bars having such length as will compensate for this stepped relation so that when all of the intermediate elements 1 are secured upon their respective 50 bars, the rear edges 5—5 of the body portions 2 will be in longitudinal alinement with each other, which will effect, therefore, the required alinement of the carbon-sheets. Such position of the latter will bring the 55 front edges of the carbon-sheets into exact alinement with each other.

It will therefore be seen that the carbon sheets may be readily attached to and de-

tached from the intermediate element 1 and the latter may be readily attached to and detached from the holding bars 9.

Furthermore, inasmuch as the device and the method of attachment of the carbons thereto does not mutilate the carbon paper, the latter may be reversed after the forward portion thereof has been used up, so as to use that portion of the carbon-sheet which was adjacent and secured to the holding device and hence could not pass around the platen roll of the type-writing machine.

In practice we prefer to make the length of the carbon-sheets substantially twice that which is necessary for writing upon a given length of form so that upon reversal a length of carbon-sheet is presented for use which will answer all the requirements of the succeeding writing operations.

What we claim is:

1. A carbon-sheet holder comprising a sheet of suitable material and adapted to be secured to the carbon-sheet operating means of a duplicating typewriter; and means for detachably securing the end portions of a carbon-sheet thereto.

2. A carbon-sheet holder comprising a sheet of suitable material cut to form a main transverse body member and a longitudinal extension; and means for detachably securing the end portion of a carbon-sheet to said body member.

3. A carbon-sheet holder comprising a flat piece of suitable material formed with a transverse body member, a longitudinal extension, and a flap portion adapted to fold over upon said body member in a longitudinal direction; and detachable means for clamping said flap portion against said member.

4. A carbon-sheet holder comprising a flat piece of suitable material formed with a transverse body member, a central longitudinal extension and two flaps, one upon each side of said extension and attached to the transverse edges of said body portion adjacent to said extension, said flaps adapted to fold over upon the face of said member; and means for securing said flaps in their folded position.

5. In a duplicating type-writing machine, the combination of a carbon-sheet operating device including a transverse bar; a carbon-sheet holder detachably secured to said bar; and a carbon-sheet detachably secured to said holder.

Signed by me this 1st day of December, 1923.

ARTHUR S. GILMAN.

Signed by me this 6th day of December, 1923.

JOHN E. DOODY.
